UNITED STATES PATENT OFFICE.

ROY ALEXANDER WEAGANT, OF DOUGLAS MANOR, NEW YORK, ASSIGNOR, BY MESNE ASSIGNMENTS, TO RADIO CORPORATION OF AMERICA, A CORPORATION OF DELAWARE.

RADIO SIGNALING APPARATUS.

Application filed July 12, 1918. Serial No. 244,584.

To all whom it may concern:

- Be it known that I, Roy ALEXANDER WEAGANT, a citizen of the United States, and resident of Douglas Manor, county of 5 Queens, city and State of New York, have invented certain new and useful Improvements in Radio Signaling Apparatus, of which the following is a specification accompanied by drawings.
- 10 This invention relates to radio signaling apparatus but more particularly to receiving apparatus and methods of reducing the interference of static disturbances or "strays." The basic principles of my invention have been set forth in my co-pending applications, Serial Numbers 157,594 and 181,458, in which I have disclosed methods and apparatus for balancing out the effects of static disturbances while retaining the 15 signals. In my earlier applications referred to, I have described the directional action of the antennæ shown, as illustrating my invention, and in my Patent No. 1,356,751, dated October 26, 1920, filed concurrently 20 herewith I have further referred to the observed phenomena, that the signals are not always of the same strength or intensity in both antennæ, while the currents due to static are substantially the same strength in each, thus producing at times a different ratio of static strength to signal strength in 25 the antennæ.
- Whether or not this ratio is the same for the antennæ does not affect my method of 30 eliminating static, which operates in accordance with the principles disclosed in my applications referred to. I generally prefer, however, to have the signals of substantially the same maximum intensity, although 35 very good results may be obtained with a different ratio of static to signal in each antenna. The variations in signal intensity may be due to other causes, as for instance, ground conditions, and perhaps 40 other reasons not thoroughly understood as yet, but the intensity of the currents due to both static and signal may be controlled to a considerable extent by suitable devices such as variable resistances. The absolute value 45 of the currents due to static in two antennæ or antennæ systems can then be made substantially equal and opposite, while the signals, being of different intensity, will give a resultant equal to their difference.
- 50 This difference of ratio between static and signal in different antennæ or antenna systems may be due to causes other than the directional action of the antennæ, or in addition to the directional action. The antennæ may each be constructed 55 differently, for instance, but in such manner that the currents due to static are substantially the same while the signals are of different intensity, due, at least in part, to the form of antenna construction. 60 For example, one antenna may extend under ground while the other lies on or above the ground, or one may extend under water and the other under ground. In such cases I have found that the ratio of static to signal may be different in each antenna. 65
- 70 The primary object of the present invention is to utilize the observed phenomena as far as possible in eliminating static at a radio receiving station in which the ratio of static to signal is different in the antennæ or antenna systems, and I am to be understood as using the terms "antenna systems" and "antenna" interchangeably throughout this specification, in describing different forms 75 of apparatus for carrying out the invention, as illustrated in the drawings in which—
- 80 Figure 1 is a diagrammatic representation of circuits and apparatus at a radio receiving station for carrying out the invention, in which two antennæ systems of different construction are employed and provided with means for securing dissimilar ratios of static to signal.
- 85 Figure 2 is a similar view of a modification in which the difference in ratio is secured by screening one antenna or antennæ system from the signal waves.
- 90 Figures 3 and 4 are modifications of Figure 2.
- 95 Figures 5 and 6 show systems in which one antenna lies under ground or partly under ground, while the other lies on or above the surface of the ground.
- 100 Figure 7 shows a system in which one antenna lies under ground and the other extends under water.
- Figure 8 shows two long, low loop an-

tennæ, one at a higher elevation above the ground than the other.

Figure 9 shows one antenna in the form of a long, low loop and the other in the form of a cage or series of loops connected by leads to the receiving apparatus.

Figure 10 shows one antenna as a cage and the other as a conductor of wire lying on or above the surface of the ground.

10 Figures 11 and 12 show forms of grounded loop antennæ.

Figure 13 illustrates a system in which both antennæ are in the form of conductors or wires lying on or above the surface of 15 the ground.

Figures 14, 15 and 16 are modifications of Figure 13.

Figure 17 shows both antennæ extending under ground, or partly under ground, and 20 partly on the surface.

Figure 18 shows a system in which the antennæ are in the form of cages connected by leads to the central receiving station, and illustrating a modified form of connections 25 for the receiving apparatus in place of a goniometer.

Referring to the drawings, and at first more particularly to Figure 1, A and B are antennæ preferably shown in the form 30 of loops or cages separated by an appreciable fraction of a wave length in the direction of desired reception and connected by leads C to suitable receiving apparatus located substantially midway between the antennæ A and B. The leads are shown broken in their length to indicate that they are 35 longer in proportion than actually shown, owing to the limitations of the sheet on which they are drawn. Tuning and con-

40 trolling apparatus for the cages A and B may be provided as illustrated in my said Patent No. 1,356,751 but I have shown condensers D preferably located in the circuits of the cages at the mid points, or in series be-

45 tween the sets of loops forming the cages. The loop antennæ or cages may be of any suitable construction but I have indicated them diagrammatically for simplicity. The leads C connecting the cages to the receiving ap-

50 paratus should preferably be arranged close together—for instance, several inches apart—in a substantially horizontal plane, for under those conditions the leads seem to pick up the least amount of static.

55 In the form of the invention shown in Figure 1 an additional cage or loop antennæ E is preferably located in a convenient position relatively to the cages A and B and, having its plane extending in the same

60 general direction as the planes of the cages A and B. For convenience, and in order to shorten the length of leads required, the cage E may be located as indicated in Figure 1 in the central region between cages

65 A and B, near the receiving apparatus.

The receiving apparatus includes the circuits of both cages A and B forming one antennæ system, and the circuit of cage E forms another antennæ system. The leads C from cages A and B are connected to the 70 coils F and F' respectively which may in turn be connected to each other at their mid points by connection H and to ground G. At the receiving station, and forming part of the receiving apparatus, are shown 75 variable resistances R, inductances L, and condensers K, connected in the circuit of the leads C for tuning and adjusting purposes, and the number and arrangement of these adjustable means may be varied, as 80 desired. Variable resistances R, inductance coils L, and condensers K are shown connected in the circuit of the cage E for adjusting and tuning purposes, and these may be varied as desired.

85 Suitable receiver circuits, including detecting means, preferably in the form of a three-element vacuum valve V, adapted to be coupled to the two antennæ systems AB and E. Any suitable means may be 90 provided for so coupling the receiver circuits, and in this instance I have shown an intermediate circuit J coupled to one of the coils L in the circuit of the antenna E by means of the coil O, and also coupled to 95 the coils F and F' in the antenna system AB by means of the coil P. A variable condenser K' may be provided in the intermediate circuit J and the receiver circuits including the vacuum valve V are suitably 100 coupled to the intermediate circuit at Q. The vacuum valve V is connected to the oscillatory circuit containing the condenser b and the valve has, as shown, the usual 105 plate circuit c, d, e, f, and in addition the oscillatory circuit c, g, h, f, although any suitable or desirable circuits may be used.

110 While I have shown the connections illustrated diagrammatically in Figure 1 for the antennæ system AB, it is to be understood that the cages AB may be connected up in any one of the arrangements I have shown in my co-pending applications Serial numbers 157, 594 and 181,458 and in my Patent No. 1,356,751 relating to the elimination of static, and the third loop E may be coupled in any suitable manner to the circuits of the antennæ system AB, and tuned in the usual manner.

115 In connection with Figure 1, two methods of adjustment and operation exist for eliminating static from the system. First, system AB is tuned and balanced in the usual way by making the currents resulting from 120 static disturbances equalize or balance out while some of the signal current remains. As a result of this adjustment, the ratio of static strength to signal strength in the system AB has been materially changed 125 from the ratio existing in either antenna A 130

or antenna B alone. The loop antenna E is then tuned and by means of the suitable resistances R or by variation in coupling, the intensity of the currents due to static in antenna E is made substantially equal to the intensity of the currents due to static which are left after balancing the system AB. By means of the coupling coils shown the residue static of system AB is made to oppose the static from system E. The reduction of the static in system E to the point where it is equal to the residue from system AB has reduced the signal in system E also to a point where it is very much less than the signal remaining after system AB has been adjusted. Therefore on opposing the signal and static currents from system E to the signal and static currents from system AB, a further increase of the signal static ratio is obtained and therefore a further improvement in working.

A second method of operation of the system shown in Figure 1, which at the time of filing this application, I have only had opportunity to use, when the space between the cages is relatively small as compared to the maximum obtainable, is to reverse the coupling of the antennæ A and B so that the signal instead of the static is balanced out of the system AB. After this has been accomplished the static currents from antenna E are adjusted to oppose and equalize the static currents from the system AB, leaving the entire signal from antenna E as a useful resultant.

If the spacing between antennæ A and B is not half wave length, then when antennæ A and B are coupled together so as to add the static, some of the signal from said antennæ will be left, and this will be the greater the more the spacing between said antennæ differs from half wave length.

This second method of operation of such a system is not claimed specifically herein, but is so claimed in my application No. 275553, filed February 7th, 1919.

In both of these methods, two antennæ or antenna systems, having initially a different signal static ratio, are coupled together or otherwise so connected as to oppose or balance out the static and leave a useful residue of signal.

In Figure 2 another form of construction is diagrammatically shown in which the signal static ratio is different in two antenna systems A and B. The antennæ are shown in the form of loops or cages which may preferably be arranged in substantially parallel planes near the receiving station, but the cages are far enough apart to permit one cage to be screened by a series of screens C of suitable material, which will substantially prevent the signal waves from affecting the antenna A for instance, assuming that the signal waves arrive in the

direction of the arrow. Static disturbances arriving from overhead substantially perpendicular to the earth's surface, will affect both antennæ simultaneously, but the static signal ratio will be different in each antenna. The static may be balanced out by suitable means retaining the signal. Suitable tuning or phase adjusting devices are shown in the circuits of the antennæ as, for instance, resistances R, inductances L, and condensers K. A detector circuit S of the usual type is shown coupled to the antennæ circuits.

Figure 3 is a modification of Figure 2 showing the cages AB in plan view and a coupling coil L' bridging across the common circuit of both cages. The detector circuits S are shown coupled to the coil L'. Suitable adjustments of the tuning means and coupling will enable the static to be balanced out, leaving the signal from one antenna B, as in the case of Figure 2.

Figure 4 is another modification of both Figures 2 and 3 showing a goniometer T at the receiving station to which the antenna circuits are connected. As hereinbefore stated in my co-pending applications, a goniometer forms a convenient instrument capable of nice adjustment for balancing out static and retaining the signals, although it is by no means a necessary instrument. In Figure 4 the stationary goniometer coils U, as shown, are connected to the antenna circuits and the condensers K are preferably included in series with the coils U for tuning purposes. The movable coil W of the goniometer pivoted at h is connected to the receiver circuits S, although if desired these receiver circuits may be in the form shown in Figure 1 including the three-element vacuum valve V. By suitable adjustment of the goniometer and the adjusting means of the circuits as shown, the static may be balanced out, leaving the signal from antenna B, it being assumed that little or no signal is received on antenna A because of the screen C.

In addition to the methods of producing a different ratio of static to signal in the antennæ or antenna systems described in connection with Figures 1 to 4 inclusive, I have discovered that such a difference in ratio may exist to a certain extent in two antennæ or antenna systems which are dissimilar in construction or differently circumstanced either as to position or adjustment, or both. This relation may exist, for instance, between one antenna or antenna system consisting of a buried wire, while the other system consists of an antenna in the form of a wire lying on or above the surface of the ground. Another example would be a system in which one antenna is buried under ground while the other antenna extends under water. In such dissimilarly constructed systems there may exist therein

initially, before the two systems are coupled or otherwise made co-operative, a difference in the signal to static ratio, and I have found that by the use of suitable adjusting means, 5 such as a resistance or resistances, the currents due to static in the two systems can be made substantially equal and opposite while the signals, since of different intensity, will produce a resultant equal to 10 their algebraic sum.

In Figure 5 I have illustrated a system in which one antenna X consists of a wire or conductor, preferably insulated, and buried in the ground for the whole or the larger 15 portion of its length while the other antenna Y consists of an insulated conductor which may be of any suitable character, extending on the surface of the ground or supported above the surface at any convenient distance. 20 The antennæ X and Y are shown connected to the stationary coils U of a goniometer T and counterpoises Z, which may consist of wires lying on the ground, are also connected to the coils U. These counterpoises 25 may be of any suitable construction and may consist of single wires extending a substantial distance from the station, or they may consist of several wires extending in fan-like shape. The antennæ and their counterpoises form antenna systems which are provided with the adjustable resistances R and inductances L, while condensers K are shown in series with the coils U. The receiver circuits (not shown) are connected 30 as usual to the movable coil W of the goniometer. The antennæ X and Y preferably extend outwardly from the receiving station substantially in line with each other and in the general direction of reception, for the 35 best results.

In the system shown in Figure 5, with the antennæ X and Y both lying in the general direction of reception from the transmitting station, one antenna will be nearer 45 to the transmitting station than the other, and it might be assumed that the system would operate equally well if both antennæ were the same distance from the transmitting station, or were constructed at any predetermined and various angles to the direction 50 of reception from the transmitting station. The facts, however, as observed by me in working with the system of Figure 5, indicate that no practical or satisfactory results can be secured unless the antennæ are 55 substantially in line with the transmitting station or extend in the same general direction of reception so that the antennæ are at different distances from the transmitting station and have an effective separation of an appreciable fraction of a wave length. The 60 effective separation is substantially equal to the distance between the middle points of the two wires forming the antennæ.

65 The difference in signal static ratio may

also exist in the construction of Figure 5, due to the fact that the wires X and Y are in fact two inverted L antennæ, one of which is directive toward, and the other directive away from the transmitting station, from 70 which it may result that the signal in one, namely, that which extends away from the station, is stronger than the signal in the other, while the static in both is substantially equal. This condition would obtain 75 regardless of whether the antennæ were under ground, on the ground, or above the surface of the earth.

Figure 6 is a modification of Figure 5 in which the antenna lying on or above the 80 surface of the ground consists of a lead cable Y' containing two insulated conductors 1 and 2 which are connected to the goniometer. In some instances I have found it desirable to connect a cross wire 3 at the 85 outer end of the cable, forming a T-shaped antenna. Otherwise Figure 6 is like Figure 5, but the antennæ of Figure 5 may also have the cross wires 3 if desired.

In Figure 7 one antenna X is shown 90 buried in the ground while the other antenna Y² is shown extending under water, as for instance under a lake, or river, or in the ocean. The antenna Y² may also be extended under water if buried in swampy 95 ground or in ground in which the water table is near the surface, as in the Everglades of Florida. The two antennæ X and Y² may be connected to a goniometer as in 100 Figure 5, for instance, with counterpoises or else the construction as shown in Figure 7 may be used, in which the antennæ are connected to each other and a connection r is made at the point s leading to ground at t. In this connection r I provide the variable 105 condenser u and coupling coil v, to which the receiver circuits w are coupled. The antennæ are provided with adjusting devices in the form of resistances R, inductances L, and condensers K. The antennæ X and Y² preferably extend in the general 110 line of reception and there will be a difference in the static signal ratio in the antennæ or antenna systems for the same reasons as stated in connection with the previous Figures 5 and 6.

With the connections shown in Figure 7 there is another possible theory of operation 115 because the two antennæ or antenna systems X and Y², being connected directly together, may be considered as one long antenna or antenna system which, when set into oscillation by the static disturbances, vibrates in the period to which it is adjusted, so that a node of potential is formed 120 approximately at its center, indicated generally as the point s. A connection represented by r between this nodal point s and the earth would be expected to carry no current due to static disturbances. The in- 125

coming oscillations, particularly from a transmitter of continuous oscillations, would not be expected to produce a node of potential at this point *s*, and consequently should give rise to signal currents in the earth connection *r*. Whether or not this is a true explanation of the observed facts in connection with the circuits of Figure 7 I am unable to say at the present time, but it is a possible explanation in addition to the well-understood theories heretofore enumerated.

It is to be understood that Figure 7 is merely illustrative and different combinations of antennæ or antenna systems may be constructed with one antenna under water and the other on or over the ground, and the antenna under water could be combined with any other suitable form of antenna like that shown at *Y'* in Figure 6, for instance. It is not deemed necessary to illustrate all the different combinations of dissimilar constructions of antennæ which could be designed or which I have actually tried myself and found to operate.

In Figure 8 I have shown an elongated loop antenna *o*, extending parallel to and near the ground in a vertical plane and connected to the goniometer *T* at one side. Another elongated loop antenna *x* of about the same vertical dimension as antenna *o* but located at a greater height above the surface of the ground is connected to the goniometer at the other side. The poles *y* may be 15 or 20 feet high, for instance, or any desired height, and I have found that the signal appears to be stronger on the high loop *x* than on the low loop *o* so that the signal static ratio is different in the two antenna systems.

In Figure 9 I have shown a loop antenna, or cage *A*, at one side connected by leads *C* to the goniometer *T* and balanced against this is an elongated loop antenna *o*, like that shown in Figure 8. Reversing switches 4 and 5 are preferably provided in the leads *C*, one at the cage *A* and the other at the receiving station, because I have found that there is apparently a best relation of the leads to the cage and of the leads to the receiving apparatus, as explained in connection with my Patent No. 1,356,751. Another reversing switch 6 is preferably provided at the receiving station for the leads connected to the two sides of the loop *o*. The usual adjusting and tuning means are provided for the two antenna systems and I have found that the static signal ratio is apparently different in the two systems *A* and *o*.

In Figure 10 I have shown one antenna in the form of a cage *B* connected at one end to ground at *G* and connected by a lead *C* at the other end to the receiving station. The other antenna consists of a wire *Y* which may lie on or above the surface of the ground, or it may be buried in the ground or extend under water, as desired. Instead

of a goniometer or some form of coupling between the receiver circuits and the antenna systems, the systems may be connected together at *s* and from this point a connection *r* may be taken to ground at *t*. This connection, from the point *s* to ground at *t*, is for the same purpose as the similar connection shown in Figure 7. Obviously the ground connection *t* in Figures 7 and 10 and the ground connection *G* in Figure 10 may have counterpoises substituted therefor if desired. The loop antenna or cage *B* may be considered as a periodic antenna because it is of the loop type while the horizontal type antenna *Y* whether above ground or under ground or under water, is aperiodic or approximately aperiodic, because all its constants are uniformly distributed and it can be set in vibration at any frequency within a wide range. Each antenna system is provided with the usual adjusting and tuning means as shown.

In Figure 11 I have shown two elongated loop antennæ *o* having their ends connected together at the points 7 and 8 and connected to the stationary coils of the goniometer *T*. These coils are also joined by the circuit 9 and connected to ground at *G*, thus forming grounded antenna systems. The ground connection *G* could be in the form of a counterpoise or counterpoises if desired.

Figure 12 is a modification of Figure 11 in which the antenna systems *o* are connected together through the coils 10 and 11 and grounded at *G* or connected to a counterpoise. Receiver circuits *S* as shown are coupled to the coils 10 and 11.

In Figure 13 two antennæ *Y* are shown lying on or above the surface of the ground and connected through the goniometer to the counterpoises *Z*. The antennæ *Y* may be any suitable insulated wires or rubber covered insulated cables, or lead sheathed cables, or any other suitable form of conductors. In this case, as in the systems of Figures 11 and 12, the different static signal ratio in the antenna systems is due mainly to the directive effect.

Figure 14 is a modification of Figure 13 in which the receiver circuits *S* are coupled to the antenna systems by ordinary coupling means instead of a goniometer, and each antenna system is connected to a counterpoise *G'*.

Figure 15 shows a modification of Figures 13 and 14 in which the antennæ *Y* of similar or dissimilar construction, that is both lying on the ground or one under ground and one over the ground for instance, are connected together at the point *s* and the connection *r* is taken from this point to the ground *t* or counterpoise, as in Figure 7 or Figure 10.

Figure 16 shows two lead cables *Y'* forming the antenna systems and connected through a goniometer *T*.

Figure 17 shows two antennæ X buried in the ground for the whole or a portion of their length and connected through a goniometer T.

5. Figure 18 shows two loops antennæ or cages A and B connected by leads C to the receiving station. As in Figure 3, a coil L' is bridged across the common circuit of the cages and the receiver circuits S are coupled 10 to this coil L' instead of using a goniometer or other connection.

In all those figures from 13 to 18 inclusive, in which the antennæ or antenna systems are substantially similar in construction at each 15 side of the receiving station, the difference in static signal ratio in the antenna is apparently due mainly to the directive action of the systems.

I claim and desire to obtain by Letters 20 Patent, the following:

1. The method of reducing interference by static disturbances in radio reception, which consists in receiving the interference and the desired signal waves in antenna 25 systems tuned to the same wave length and having different ratios of static strength to signal strength, and balancing out the static while retaining the signal.

2. At a radio transmission receiving station, a plurality of antennæ having an effective separation of a substantial fraction of a wave length in the general direction of reception of signals, the ratio of static strength to signal strength being different 35 in each antenna, and receiving apparatus connected to said antennæ for balancing out the static while retaining the signal.

3. At a radio transmission receiving station, a plurality of antennæ, at least one of 40 which is substantially aperiodic, arranged to have directional action for horizontally received waves in a definite direction, the ratio of static strength to signal strength being thereby different in one antenna 45 from that in the other and receiving apparatus connected to said antennæ for balancing out the static while retaining the signal.

4. At a radio transmission receiving station, a plurality of substantially aperiodic antennæ arranged to have directional action for horizontally received waves in a definite direction, the ratio of static 55 strength to signal strength being thereby different in one antenna from that in the other and receiving apparatus connected to said antennæ for balancing out the static while retaining the signal.

5. At a radio transmission receiving station, a plurality of counterpoised antennæ having an effective separation of a substantial fraction of a wave length in the general direction of reception of signals, the ratio of static strength to signal strength being

different in each antenna and receiving apparatus connected to said antennæ for balancing out the static while retaining the signal. 65

6. At a radio transmission receiving station, a plurality of antennæ having an effective separation of a substantial fraction of a wave length in the general direction of reception of signals, the ratio of static strength to signal strength being different in each antenna, receiving apparatus connected to said antennæ for balancing out the static while retaining the signal, and counterpoise means connected to said antennæ at the ends adjacent the receiving apparatus. 70 75

7. In a radio receiving system, the combination of oppositely directed collectors, a phase adjusting device in circuit with one of said collectors, and a resistance mutually connecting said phase adjusting device and the opposite collector, means for varying the ratio of signal strength to stray strength in the opposite collector and a receiving apparatus adjustably connected between said resistance and the ground. 80 85 90

8. At a radio transmission receiving station, a plurality of differently circumstanced antennæ free from tuning to different wave lengths with respect to each other, the ratio of static strength to signal strength being thereby different in one antenna from that in the other, and receiving apparatus connected to said antennæ for balancing out the static while retaining the signal, phase adjusting devices in connection with the receiving apparatus, and means for controlling the intensity of the currents due to both static and signal. 95 100

9. The method of reducing interference by static disturbances in radio reception, which consists in receiving the interference and desired signal waves as currents of the same frequency in antenna systems having different ratios of static strength to signal strength, and balancing out the static 110 while retaining the signal. 105

10. The method of reducing interference by static disturbances in radio reception, which consists in arranging a plurality of antenna systems free from tuning to different wave lengths with respect to each other to have a different ratio of static strength to signal strength, receiving the interference and the desired signal waves in such antenna systems and balancing out the static while 115 retaining the signal. 120

11. In a radio receiving system, in combination, a plurality of collectors free from tuning to different wave lengths with respect to each other and adapted to have different ratios of static current to signal current respectively, and means adapted to cause the currents due to static in the respective col- 125

lectors to oppose and substantially neutralize each other leaving the currents due to signal unneutralized.

12. In a radio receiving system, the combination of oppositely directed collectors, a resistance connecting said collectors, and a receiving apparatus adjustably connected between said resistance and ground.

In testimony whereof I have signed this specification in the presence of two subscribing witnesses.

ROY ALEXANDER WEAGANT.
